UNITED STATES PATENT OFFICE

BENJAMIN R. HARRIS, OF CHICAGO, ILLINOIS

EMULSION

No Drawing.

Application filed September 30, 1931. Serial No. 566,159.

My invention relates in general to improved emulsions and emulsion improving substances. It relates more specifically to an improved non-spattering type of margarine and anti-spattering substances for use with margarine and is a continuation in part of application Serial No. 476,935 filed August 21, 1931. The latter application is a division of application Serial No. 475,622, filed August 15, 1930 as a continuation in part of application Serial No. 383,143 filed August 2, 1929.

By means of my new products I am able to impart superior qualities to many types of emulsions, particularly to emulsions of fats and oils used for culinary purposes, but I shall explain the invention in connection with improvements in margarine. Those skilled in the art are referred to my co-pending application, Serial Number 566,156, filed September 30, 1931, as a continuation in part of application Serial No. 475,622 for a more complete disclosure of certain details of the invention than is made herein. In general the present invention represents a specific embodiment of the main invention disclosed in the co-pending application above referred to, and while the present disclosure is substantially complete insofar as it describes the invention, and supports the claims, those interested in the art are referred to the co-pending case for a more complete disclosure of the basic concept of the invention.

The principal object of my present invention is to improve such forms of emulsion as margarine.

Another object is to reduce the spattering of margarine when used for frying purposes and generally improve its frying behavior.

Other objects and features of the invention will be apparent from a consideration of the following detailed description.

As was disclosed in my co-pending applications I have discovered a large class of chemical compounds which may be used to impart improved characteristics to all types of water-oil emulsions, particularly those used for cooking purposes, and other types of culinary fat preparations. These substances have several characteristics in common which make them very valuable in their use with margarine. These substances are compatible with mild acids and in particular with lactic acid in the concentration and under the conditions existing in margarine. They are in

general difficultly soluble in oils and fats and aqueous media and in many cases are substantially insoluble. This makes it possible to use those compounds, particularly the compounds which are sparingly soluble in both aqueous and oleaginous media, in very small quantities, as they may be considered to concentrate at the water-oil interface of the emulsion rather than be freely dissolved in either the water or oil phase. These substances are semi-colloidal or truly colloidal in character and are frequently colloidally dispersible in aqueous and/or oleaginous media. They are, moreover, substantially non-volatile at margarine frying temperatures and so will remain in the margarine and perform their function during frying.

One of the most important characteristics of these compounds is the presence in the molecule of the two types of groups in balanced relation to each other, one group being hydrophylic or water wetting in character, and the other group being lipophylic or fat wetting in character. These groups must exist in the molecule in such a state of balance that they will function at the water-oil interface in the intended manner. Presumably these substances orientate themselves at the interface, by reason of the balance of the two types of groups, but it is understood that the invention does not depend upon this explanation.

My co-pending application treats exhaustively of the manner in which the balance between the two groups may be determined so that without tests of any kind it is possible for the skilled colloid chemists to pick out compounds which cannot function effectively as anti-spatterers, as well as compounds which clearly will be effective as anti-spatterers.

However, there are compounds of such character that the state of balance existing between the two groups in the molecule is preferably determined by a simple quick test.

The balance of the hydrophile-lipophile groups in the compounds which I apply in my invention is one of the characteristics and determinants of the class of substances which I employ.

The test which I have chosen as a means for determining the hydrophile-lipophile balance in organic compounds, I call the

312

2

1,917,259

“spoon test”. It is carried out as follows: From 0.05 to 0.50 gr. of the material or substance in question is introduced into a porcelain mortar, wetted and ground into a smooth paste or solution with a pestle with a minimum proportion of water; two to five drops generally will suffice.

An ordinary margarine such for example as one made from vegetable oils, and fats and cultured skinned milk and which possesses the usual property of spattering during frying is selected. Ten grams of this margarine are then introduced in small portions into the mortar and macerated thoroughly with the paste first prepared until the entire ten gram portion is thoroughly and uniformly intermixed with the material in the mortar. Two grams of this mixture are introduced into a tablespoon and held directly over a free flame such for example as a Bunsen flame, one or two inches long, in such a position that the point of the flame just about reaches the bottom of the spoon. A clean sheet of paper is placed on the bottom of the burner by inserting the stem of the Bunsen burner prior to lighting through a hole made in the center of the paper and allowing the paper to drop to the base of the burner to catch the margarine splashed out during the heating. The mixture in the spoon is heated until all of the water is boiled off and the ebullition ceases and the spots on the paper observed.

If this treated margarine spots the paper to the same extent as the untreated margarine from which the former was prepared, then the lipophile and hydrophile groups of the compound are not balanced. The number and size of spots on the paper or added weight can be readily determined.

If the increase in weight of the paper or the number and character of the spots produced on the paper up until all the water has boiled off are less than that produced by similarly heating two grams of the original untreated margarine employed for the test, then the material or substance in question has balanced hydrophile-lipophile groups. The expression “balanced lipophile and hydrophile groups” used in the claims is to be interpreted in terms of the above de-

ing compounds of the present invention are entirely non-nitrogenous, but if they contain any nitrogenous group, it should be devoid of the nitrogenous linkage expressed in the following formula

70

wherein “O” represents oxygen, “X” stands for phosphorus in the form of its oxygenated acid radicals such as phosphoric phosphorus, etc., “C” represents carbon, “H” is hydrogen, “w” represents a small whole number, and “N” is trivalent or pentavalent nitrogen and the terminal oxygen indicated above is linked directly to carbon.

In my co-pending application, Serial No. 566,158, filed September 30, 1931, I describe and claim certain types of nitrogenous compounds which can be used with my invention. In my present application I am interested principally in compounds containing phosphorus.

Examples of some of the phosphatic materials which I have used as anti-spattering agents, many of them not known heretofore, are as follows:

55

scribed “spoon test”, and in the light of the entire disclosure.

My present invention relates to a specific class of compounds in which the hydrophile function is exercised primarily by a phosphatic group, that is, a group containing phosphorus in the form of its oxygenated acid radicals. Preferably, the anti-spatter-

75

80

85

90

95

100

105

110

115

120

125

130

Calcium tricinolein phosphite

It is to be noted that in every case, the 10 anti-spattering agent has been produced by associating in a given molecule a lipophile group with a hydrophile group, wherein the hydrophile function is supplied primarily by a phosphorus containing radical. However, the conclusion must not be drawn from 15 this that any random combination of a hydrophobic phosphorus containing radical or its metal derivative with a lipophile group will give an anti-spatterer.

20 Examples of molecules, with phosphorus containing hydrophile groups as well as lipophile groups, but which nevertheless are not anti-spatterers are as follows:

25

Class "A"

30

35

Class "B"

40

In the case of compounds of both class 45 "A" and class "B", anti-spattering powers are lacking because of inadequate balance between the lipophile and hydrophile groups. In the case of compounds of class "A", the hydrophile group dominates and is inadequately balanced by the lipophile group, that 50 is, the lipophile characteristics of the latter are too weak to adequately balance and coact with the hydrophile group. In the case of substances of class "B", the reverse situation exists and anti-spattering power is absent because the lipophile group is dominant and is inadequately balanced by the hydrophile group.

The examples of phosphatic anti-spatterers 55 listed above, as well as other phosphatic substances which can be employed for the purpose which I have used successfully, I prepared by a number of different methods which are adequately described in the scientific and technical literature, and which methods are readily available to skilled chemists.

The compounds described above are of unusual importance in connection with their use with water-oil emulsions for all kinds, but they have a particular adaptation for 60 use with all culinary emulsion products such

as margarine. Commercial margarine after being treated with my anti-spattering agent, when fried in a pan exhibits improved frying behavior in that it allows its water to boil off quietly, fries in a pleasing and comparatively quiet manner with the formation of considerable turbid froth and foam after the manner of butter, reduces the tendency of the curd to stick to the bottom of the frying pan, and reduces the amount of material which escapes from the pan by spattering. Untreated margarine on the other hand when fried bumps turbulently, sputters noisily and foams comparatively little. Also what little foam there is, is transparent and of an entirely different character from that obtained from margarine previously treated with an anti-spatterer.

My emulsion improvers may be introduced in the margarine in a number of ways, as long as a satisfactory dispersion is obtained. For instance, the main constituents of margarine are edible oils and fats and cultured milk, and the anti-spattering or improving compounds may be introduced either into 90 the oils or milk in any suitable manner. They may also be introduced into the churn during the production of the emulsion in its liquid state, care being taken to bring about the necessary dispersion. Or, the anti-spattering material may be used in a dry condition and mixed with the salt which is worked into the crystallized margarine, or the anti-spattering material may be made into a paste with the milk and kneaded in, or blended into the 95 margarine.

Generally speaking, the compounds which I am using in connection with this invention are: phosphoric acid esters of high molecular weight organic compounds which will balance the phosphoric acid radical. It is to be noted that in each case, in the examples given above, the phosphorus containing hydrophile group is at or near an end of the molecule. These compounds may be represented structurally as follows

115

in which "O" is oxygen, "P" is phosphorus, "X" is an edible cation such as hydrogen, sodium, potassium, calcium, or the like, "Y" is either an edible cation or an organic radical, and "w" is a whole number.

Thus the above compounds may be phosphoric acid esters of a high molecular alcohol such as cetyl alcohol, or it may be a phosphoric acid ester of a polyalcohol and/or its substitution products such as, for example, a phosphoric acid ester of glycol or diethylene glycol in which one OH is esterified with a higher fatty acid such as stearic acid, or com-

120

125

130

312 4

1,917,259

bined in an ether linkage with a high alcohol such as cholesterol. Thus for example, a phosphoric acid ester of stearyl diethylene glycol, a phosphoric acid ester of monostearyl glycerol, or a phosphoric acid ester of cholesterol-diethylene glycol.

It must not be inferred from the preceding part of this specification that every anti-spattering substance of the character herein disclosed must be insoluble in oleaginous and/or aqueous media. It is true that the greater number of anti-spattering compounds of the present invention are substantially insoluble in these media, but there are a limited number of water soluble compounds which if used in sufficiently larger proportions may have an effect in reducing spattering during frying.

It appears that in a given homologous series, there is a point or range at which lipophile and hydrophile characteristics are so balanced that an optimum power for the prevention of spattering is imparted to the molecule. Going from this point higher in the series, in the direction of increasing molecular weight in the lipophile group with a given phosphate group, the anti-spattering power diminishes, because of excessive lipophile characteristics in the molecule; going down from this point or range lower in the series, anti-spattering power again diminishes, because of the excessive hydrophile characteristics in the molecule; the tendency to dissolve in water concurrently increases. In certain homologous series, however, there are cases of water soluble substances which can function as anti-spatterers. Examples of water soluble phosphorus compounds which may be used as anti-spatterers are

In general it is true, other things being equal, that a water soluble substance is not as effective as one that is not freely soluble in water. It is also true that the total number of available anti-spatterers not soluble in water is greater than the number of soluble ones. This is apparent from the following consideration. Generally, water solubility is negligible in anti-spatterers with a relatively large number of carbons in the lipophile group. However, below ten or twelve carbons, for example, the tendency for solubility in water gradually increases and in the range, four to seven or eight carbons, the anti-spatterers are generally freely soluble in water. Below four carbons, almost invariably, the lipophile group is too weak to balance the hydrophile group and anti-spattering power is absent. It is evident therefore, that the total number of possible freely wa-

ter soluble anti-spatterers is small as compared with the total number of possible anti-spatterers not soluble in water.

In descending in any given homologous, anti-spattering series there is a gradual transition, and the change in any one carbon interval is not great, there is a gradual diminishing from the optimum downward, and finally, very low in the series, anti-spattering power vanishes. 70 75

As to the specific application of the invention to margarine and other emulsions or oleaginous culinary preparations, it is clear that since there are many phosphatic compounds containing balanced hydrophile and lipophile groups, it is impractical and unnecessary to list each particular combination of groups which can be used in accordance with my invention. Moreover, while I leave something to the skill of persons applying my invention, my description is wholly sufficiently exhaustive, particularly when considered with respect to my prior applications, to enable those skilled in the art to successfully practice the same.

The term "non-spattering margarine" as used in the claims is employed to designate a margarine, the frying behavior of which is improved by the addition thereto of the novel materials of my invention herein described to reduce spattering. 95

The term "margarine" as employed in the claims includes plastic emulsions of vegetable or animal oleaginous substances or mixtures thereof, with aqueous materials such as water, sweet or ripened milk, and with or without coloring matter or other addition agents. 100

What I claim as new and desire to protect by Letters Patent of the United States is:

1. A non-spattering margarine including oleaginous media and aqueous media and having included therein a proportion of a non-nitrogenous chemical compound characterized by a coaction in its molecule of balanced lipophile and hydrophile groups, and represented by the structure 110

in which "O" is oxygen, "P" is phosphorus, "X" is an edible cation, "Y" is either an edible cation or an organic radical, "R" is a lipophile radical including an ether group, and "w" is a small whole number. 120

2. A non-spattering margarine having an oleaginous phase and an aqueous phase, and having included therein a proportion of a non-nitrogenous compound in the form of a phosphoric acid ester of a high molecular weight alcohol, said compound having balanced hydrophile and lipophile groups. 125

3. A non-spattering margarine having an oleaginous phase and an aqueous phase, and

having included therein a proportion of a non-nitrogenous compound in the form of a phosphoric acid ester of a derivative of glycerine of high molecular weight, said 5 compound having balanced lipophile and hydrophile groups.

4. A non-spattering margarine having an oleaginous phase and an aqueous phase, and having included therein a proportion of a 10 non-nitrogenous substance in the form of a phosphoric acid ester of a glycol derivative, said compound having balanced lipophile and hydrophile groups.

5. A non-spattering margarine having an 15 oleaginous phase and an aqueous phase, and having included therein a proportion of a non-nitrogenous substance in the form of a phosphoric acid ester of a higher fatty acid glycerol derivative, said compound having 20 balanced lipophile and hydrophile groups.

6. A non-spattering margarine having an oleaginous phase and an aqueous phase, and having included therein a proportion of a non-nitrogenous substance in the form of a 25 phosphoric acid ester of a higher fatty acid glycol derivative, said compound having balanced lipophile and hydrophile groups.

7. A non-spattering margarine having an oleaginous phase and an aqueous phase, having 30 included therein a phosphoric acid ester of a stearic acid ester of glycol, said phosphoric acid ester having balanced lipophile and hydrophile groups.

8. A non-spattering margarine having an oleaginous phase and an aqueous phase, and a proportion of a phosphoric acid ester of 35 stearyl diethylene glycol, said phosphoric acid having balanced lipophile and hydrophile groups.

40 9. A non-spattering margarine having an oleaginous phase and an aqueous phase, and having a proportion of a non-nitrogenous phosphoric acid ester of a higher aliphatic derivative of glycerine, said phosphoric acid ester having balanced lipophile and hydrophile groups.

10. A non-spattering margarine having an oleaginous phase and an aqueous phase, and having included therein a non-nitrogenous 50 phosphoric acid ester having balanced lipophile and hydrophile groups.

11. A non-spattering margarine having an oleaginous phase and an aqueous phase, and having a proportion of a non-nitrogenous 55 phosphoric acid ester of monostearyl glycerol, said phosphoric acid ester having balanced lipophile and hydrophile groups.

12. A non-spattering margarine having an oleaginous phase and an aqueous phase, and 60 having included therein a phosphoric acid ester of cholesteryl diethylene glycol, said phosphoric acid ester having balanced lipophile and hydrophile groups.

13. A non-spattering margarine having an 65 oleaginous phase and an aqueous phase, and

having included therein a sodium salt phosphoric acid ester of palmityl alcohol, said phosphoric acid ester having balanced lipophile and hydrophile groups.

14. A non-spattering margarine containing an oleaginous phase and an aqueous phase and having included therein a proportion of an improving agent comprising a non-nitrogenous substance characterized by a coaction in its molecule of balanced lipophile and hydrophile groups, and in which the hydrophile function is imparted to the molecule primarily by a group containing phosphorus. 70

15. A non-spattering margarine containing an oleaginous phase and an aqueous phase and having included therein a proportion of an improving agent, comprising a non-nitrogenous substance, characterized by co-action in its molecule of balanced lipophile and hydrophile groups and represented by the structure 75

in which "O" is oxygen, "P" is phosphorus, "X" is an edible cation, "Y" is either an edible cation or an organic radical, "w" is a small whole number, and "R" is an organic lipophile group. 80

16. A non-spattering margarine containing an oleaginous phase and an aqueous phase and having included therein a proportion of an improving agent comprising a non-nitrogenous substance, characterized by a co-action in its molecule of balanced lipophile and hydrophile groups and represented by the structure 85

in which "O" is oxygen, "P" is phosphorus, "X" is an edible cation, "Y" is either an edible cation or an organic radical, "w" is a whole number, and "R" is a lipophile alkyl radical including an ester group. 95

17. A non-spattering margarine containing an oleaginous phase and an aqueous phase and having included therein a proportion of an improving agent comprising a non-nitrogenous substance, characterized by co-action in its molecule of balanced lipophile and hydrophile groups and represented by the structure 100

in which "O" is oxygen, "P" is phosphorus, "X" is an edible cation, "Y" is either an edible cation or an organic radical, "w" is a small whole number, and "R" is a lipophile radical including an ester or an ether group. 105

18. A non-spattering margarine including an oleaginous phase and an aqueous phase, 110

3126

1,917,259

and having included therein a proportion of a water soluble non-nitrogenous substance characterized by balanced lipophile and hydrophile groups, and represented by the formula

10 in which "O" is oxygen, "P" is phosphorus, "X" is an edible cation, "Y" is either an edible cation or an organic radical, and "R" is an organic lipophile radical with at least four carbon atoms, and "w" is a small whole number.

15 19. A non-spattering margarine including an oleaginous phase and an aqueous phase, and having included therein a relatively small amount of monobutyl disodium phosphate

20 20. A non-spattering margarine having an oleaginous phase and an aqueous phase, and having included therein a proportion of a non-nitrogenous water soluble substance characterized by a coaction in its molecule of balanced lipophile and hydrophile groups, in which the lipophile group has at least four 25 carbons, and wherein the hydrophile function is imparted to the molecule primarily by a group containing phosphorus.

25 21. An emulsion including an oleaginous phase, an aqueous phase, and a proportion of 30 a non-nitrogenous chemical compound characterized by a coaction in its molecule of balanced lipophile and hydrophile groups, and represented by the structure

35 in which "O" is oxygen, "P" is phosphorus, "X" is an edible cation, "Y" is either an edible 40 cation or an organic radical, "R" is a non-aromatic relatively high molecular weight 45 lipophile radical including an ether group, and "w" is a small whole number.

40 22. An emulsion including an oleaginous phase, an aqueous phase, and a proportion of 45 a non-nitrogenous compound in the form of a phosphoric acid ester of a high molecular weight alcohol, said compound having balanced hydrophile and lipophile groups, the 50 lipophile group being a non-aromatic relatively high molecular weight radical.

45 23. An emulsion including an oleaginous phase, an aqueous phase, and a proportion of 55 a non-nitrogenous compound in the form of a phosphoric acid ester of a derivative of glycerine of high molecular weight, said compound having balanced lipophile and hydrophile groups, the lipophile group being a non-aromatic relatively high molecular 60 weight radical.

24. An emulsion including an oleaginous phase, an aqueous phase, and a proportion of a non-nitrogenous substance in the form of a phosphoric acid ester of a glycol derivative, said compound having balanced lipophile and hydrophile groups. 70

25. An emulsion including an oleaginous phase, an aqueous phase, and a proportion of a non-nitrogenous substance in the form of a phosphoric acid ester of a higher fatty acid glycerol derivative, said compound having balanced lipophile and hydrophile groups. 75

26. An emulsion including an oleaginous phase, an aqueous phase, and a proportion of a non-nitrogenous substance in the form of a phosphoric acid ester of a higher fatty acid glycerol derivative, said compound having balanced lipophile and hydrophile groups. 80

27. An emulsion including an oleaginous phase, an aqueous phase, and a proportion of a non-nitrogenous phosphoric acid ester of a higher aliphatic derivative of glycerine, said phosphoric acid ester having balanced lipophile and hydrophile groups. 85

28. An emulsion including an oleaginous phase, an aqueous phase, and a proportion of a non-nitrogenous substance characterized by coaction in its molecule of balanced lipophile and hydrophile groups, and represented by the structure 90

95 in which "O" is oxygen, "P" is phosphorus, "X" is an edible cation, "Y" is either an edible cation or an organic radical, "w" is a small whole number, and "R" is an organic non-aromatic relatively high molecular weight lipophile group. 100

100 29. An emulsion including an oleaginous phase, an aqueous phase, and a proportion of a non-nitrogenous substance, characterized by a coaction in its molecule of balanced lipophile and hydrophile groups and represented by the structure 105

110 in which "O" is oxygen, "P" is phosphorus, "X" is an edible cation, "Y" is either an edible cation or an organic radical, "w" is a whole number, and "R" is a lipophile alkyl radical including an ester group. 115

115 30. An emulsion including an oleaginous phase, an aqueous phase, and a proportion of a non-nitrogenous substance, characterized by coaction in its molecule of balanced lipophile and hydrophile groups and represented by the structure 120

125 in which "O" is oxygen, "P" is phosphorus, "X" is an edible cation, "Y" is either an 130

edible cation or an organic radical, "w" is a small whole number, and "R" is a non-aromatic relatively high molecular weight lipophile radical including an ester or an ether group.⁵

31. An emulsion including an oleaginous phase, an aqueous phase, and a proportion of a water soluble non-nitrogenous substance, characterized by balanced lipophile and hydrophile groups, and represented by the formula

in which "O" is oxygen, "P" is phosphorus, "X" is an edible cation, "Y" is either an edible cation or an organic radical, "R" is an organic non-aromatic relatively high molecular weight lipophile radical with at least four carbon atoms, and "w" is a small whole number.

In witness whereof, I hereunto subscribe
my name this 26 day of Sept., 1931.

BENJAMIN R. HARRIS.
